Patented Mar. 13, 1900.

U. TRANSUE.

SASH LOCK.

(Application filed Sept. 20, 1899.).

(No Model.)

UNITED STATES PATENT OFFICE.

URIAH TRANSUE, OF MINSI, PENNSYLVANIA, ASSIGNOR OF ONE-THIRD TO
THEODORE B. DRAKE, OF EAST STROUDSBURG, PENNSYLVANIA.

SASH-LOCK.

SPECIFICATION forming part of Letters Patent No. 645,441, dated March 13, 1900.

Application filed September 20, 1899. Serial No. 731,116. (No model.)

To all whom it may concern:

Be it known that I, URIAH TRANSUE, a citizen of the United States, residing at Minsi, in the county of Monroe and State of Pennsylvania, have invented a new and useful Sash-Lock, 5 of which the following is a specification.

This invention relates to window-sashes of that class embodying a rack-and-pinion mechanism for adjusting the sash; and the object 10 of the present invention is to provide a new and improved means for locking the sash at any predetermined position.

To this end the invention consists in the combination and arrangement of parts, as will 15 be hereinafter more fully described, shown in the accompanying drawings, and particularly pointed out in the appended claim.

In the drawings, Figure 1 is an elevation of a portion of a window sash and frame having 20 the improvements applied thereto. Fig. 2 is an elevation with the face-plate of the device removed. Fig. 3 is a longitudinal sectional view on the line *xx*, Fig. 2. Fig. 4 is a transverse sectional view on the line *yy*, Fig. 2. 25 Fig. 5 is a detail perspective view of the operating thumb-lever. Fig. 6 is a detail perspective view of a modified form of operating-lever.

Corresponding parts are designated by like 30 reference characters in all the figures of the drawings.

Referring to the accompanying drawings, 1 designates a window-frame, and 2 a window-sash, both of which are of common or ordinary 35 construction. As best shown in Figs. 2 and 4, one of the window-jambs 3, preferably the left-hand jamb, is provided with a longitudinal groove 4, extending the entire length of its exposed face, against which the sash is 40 adapted to slide. Fitted within this groove is a fixed rack 5, having the outer edges of its teeth flush with the face of the jamb, so as not to interfere with the movement of the sash.

In the outer face of the sash, next to the 45 rack, is provided a recess 6, which opens out through the outer edge of the sash, and mortised in the edge of the sash is a plate 7, having a lateral extension 8 intermediate of its ends, which is adapted to fit snugly within 50 in the recess 6, flat against the back thereof. Two transversely-alined openings 9 and 10,

respectively, are provided in the extension of the plate 7, and the latter is cut away, as at 11, in its upper edge and opposite the extension 8 for the purpose of exposing a portion 55 of the rack to the interior of the recess 6. Mounted in the round opening 9, which is next to the plate 7, is a pinion 12, adapted to be in mesh with the rack 5. The inner journal 13 is formed integral with the pinion and is provided 60 with an annular shoulder 14, which bears against the outer face of the extension of the plate 7, and this journal is comparatively long to permit of the recess 6 being deep enough to accommodate the means for 65 locking the pinion, as will be hereinafter more fully described. A face-plate 15 is fastened to the face of the window-sash, covering the recess 6 and provided with an opening 16, which is adapted to receive the outer short 70 integral journal 17 of the pinion 12, and thereby mount the same in position. The outer edge of the groove formed in the jamb 3 is cut away, as at 12^a, near the lower end of the groove, as shown in Fig. 2, so that the pinion 75 may be placed in position, and then the frame 1 is secured in place, covering up the cut-away portion.

The ratchet mechanism for locking the pinion is shown in detail in Fig. 5 and comprises 80 a bowed lever 18, having at its upper end a transverse fulcrum-lug 19, which is provided with a notch 20 in its outer edge. At its opposite lower end the lever is formed into an operating thumb-piece 21, and intermediate 85 of its ends is provided a transverse stem 22, which extends in the same direction as the fulcrum-lug and is longer than the latter. This stem is provided at opposite sides thereof and intermediate of its ends with the alined 90 hooked ratchet-teeth 23, which extend longitudinally of the lever and are adapted to normally engage the teeth of pinion 12 to hold the same locked against turning. The fulcrum-lug 19 is received within an opening 24, 95 formed in the face-plate near its upper end and to one side thereof opposite the opening for the pinion, and the notch 20 embraces the upper edge of the opening 24, whereby the lever is fulcrumed upon the face-plate, and the stem 22 is slidably received through an opening 25, the ratchet-teeth 23 being located 100

beyond the inner face of the plate and the lever upon the outer face thereof. It will be noted that the face of the window-sash above the recess 6 therein and beneath the face-
 5 plate is provided with a notch 26 to receive the inner end of the fulcrum-lug, and the back of the recess 6 is provided with an opening 27 to accommodate the end of the stem 22 at the inward limit of its movement. A coiled
 10 spring 28 encircles the stem 22, bearing at its inner end against the back of the recess 6 and at its other end against the inner side of the ratchet-teeth 23, whereby the lever is normally held at its extended position and the
 15 ratchet-teeth are held in engagement with the pinion to lock the same.

The parts being assembled, as hereinbefore described, to raise the window-sash the lever 18 is operated by pressing inward upon the
 20 thumb-piece 21, whereby the ratchet-teeth 23 are carried inward out of engagement with the pinion, and the latter is free to be revolved. The window-sash can then be raised as usual, the pinion traveling upon the rack, and when the sash has been raised to the desired height the pressure is relieved from the thumb-piece and the spring will force the lever outward and again engage the ratchet-teeth with the pinion, and the sash will be
 25 held at the adjusted position.

The lever 18 may be dispensed with, as shown in Fig. 6, and the stem 22 provided with a button or head 29 to receive the pressure of the hand of the operator for disengaging the ratchet-teeth from the pinion. When this form is used, the stem should be
 30 angular in cross-section, and the opening 25, which receives the stem, should also be angular in form to prevent the stem from turning when the teeth thereof are disengaged from the pinion.

It will be noted that the present device may be applied to any window-sash without altering the construction thereof, it being simply necessary to provide a recess in the face of the sash to receive the pinion and a groove in one of the jambs to receive the rack. All of the parts are inclosed within the side rail of the sash and are therefore not subject to displacement nor damage. The device is 45 preferably mounted near the lower left-hand side of the sash, is comparatively small and light, and forms an effective sash-lock when the sash is closed.

Changes in the form, proportion, size, and the minor details of construction within the scope of the appended claim may be resorted to without departing from the spirit or sacrificing any of the advantages of this invention. 50

Having thus described the invention, what I claim is—

In a sash-fastener, the combination of a rack, a pinion in mesh therewith, a casing inclosing the pinion, a face-plate for the casing, 65 and provided with a pair of opposite openings, a stem slideable through one of the openings, and provided with teeth in detachable engagement with the pinion, and an operating-lever connected to the stem, and having a fulcrum-lug received within the other opening in the face-plate, and provided with a notch embracing one edge of said opening, substantially in the manner shown and described. 70

In testimony that I claim the foregoing as my own I have hereto affixed my signature in the presence of two witnesses.

URIAH TRANSUE.

Witnesses:

A. K. STONE,
JESSE RAUSBERRY.
